J. F. NELSON,
RIGHT ANGLE HANPIPE FOR DENTAL ENGINES,
APPLICATION FILED MAR. 28, 1919.

1,332,744.

Patented Mar. 2, 1920.

Inventor

J. F. Nelson

By *Alvarez Murphy Jr.*, attorney.

UNITED STATES PATENT OFFICE.

JOSEPH F. NELSON, OF SCOTT CITY, KANSAS.

RIGHT-ANGLE HANDPIECE FOR DENTAL ENGINES.

1,332,744.

Specification of Letters Patent.

Patented Mar. 2, 1920.

Application filed March 28, 1919. Serial No. 285,746.

To all whom it may concern:

Be it known that I, JOSEPH F. NELSON, a citizen of the United States, residing at Scott City, in the county of Scott and State 5 of Kansas, have invented certain new and useful Improvements in Right-Angle Handpieces for Dental Engines; and I do hereby declare the following to be a full, clear, and exact description of the invention, such as 10 will enable others skilled in the art to which it appertains to make and use the same.

This invention relates to right angle handpieces for dental engines, and the primary object of the invention is to provide 15 an improved means for mounting the tool carrying sleeve in the tool support, so as to provide a relatively large area of bearing surface for the same and thus increase the wear of the parts.

20 Another object of the invention is to provide an improved means for taking up the wear of the tool carrying sleeve, so as to effectively increase the life thereof.

A further object of the invention is to 25 provide an improved means for holding the bur or other tool in the tool carrying sleeve, whereby the same can be readily removed or placed in position in the handpiece.

A still further object of the invention is 30 to provide an improved right angle handpiece of the above character, which is durable and efficient in use, one that is simple and easy to manufacture, and one that can be placed upon the market at a reasonable 35 cost.

With these and other objects in view, the invention consists in the novel construction, arrangement and formation of parts, as will be hereinafter more specifically described, 40 claimed and illustrated in the accompanying drawings, forming a part thereof, in which:

Figure 1 is a side elevation of the improved handpiece.

Fig. 2 is a vertical central longitudinal 45 section through the same.

Fig. 3 is an enlarged vertical section through the tool carrying sleeve, showing a tool positioned therein.

Referring to the drawings in detail, 50 wherein similar reference characters designate corresponding parts throughout the several views, the numeral 1 indicates the handpiece, which supports the shaft 2 in the ordinary manner and carries at the outer 55 end thereof the tool support 3, which has the internally threaded socket 4 by means of

which the tool support is held in position. The tool support also includes the transverse socket 5 in which is removable fitted the tool carrying sleeve 6 having frusto-conical enlargements 7 and 8 formed on the terminals thereof, which form enlarged bearing surface for the sleeve. The smaller ends of the frusto-conical portions are disposed in opposite relation to each other, and the lower frusto-conical member 8 has the upper surface thereof provided with teeth, so as to form a cogwheel 9, which is adapted to mesh with a cogwheel 10 carried by the outer end of the shaft 2, whereby the sleeve 70 may be readily rotated by the shaft.

The terminals of the transverse sockets 5 are provided with internal screw threads 11, in which are fitted the upper and lower caps 12 and 13. Each of the caps is provided 75 with an annular outstanding knurled flange 14, whereby the same may be readily grasped and unthreaded from the sockets 5 when so desired. The caps 12 and 13 are internally tapered, as at 15, so as to conform to the configuration of the frusto-conical enlargements 7 and 8 to form bearings for the same. The lower cap 13 is provided with a central aperture 16, so that the tool 17 may be readily inserted in the tool carrying 80 sleeve 6.

The tool 17 is of the ordinary construction and the upper end thereof is provided with a flat portion 18, the purpose of which will be hereinafter more fully described. The upper end of the tool is also provided 90 with a groove 19 for the reception of the locking pin 20, which will be hereinafter more fully described. The tool carrying sleeve 6 adjacent to the upper end thereof has secured thereto a pin 21, which extends through the bore of the sleeve and this pin is adapted to engage the flattened portion 18 of the tool when the same is inserted in the sleeve to prevent independent rotation 95 thereof in relation to the sleeve.

The tool carrying sleeve 6 is provided 100 with an inwardly extending opening 23, which communicates with the bore of the sleeve adjacent to the upper end thereof and slidably receives the locking pin 20, which has the inner end thereof tapered as at 24 and the tapered end is adapted to fit in the groove 19 formed in the tool 18 for holding the same in position in the sleeve.

110 In operation of the improved device, the tool carrying sleeve is inserted in the socket

5 and the caps 12 and 13 are threaded into position and the caps support the same for rotary movement in the socket. When it is desired to insert the tool 17 in the tool carrying sleeve 6, the upper cap 12 is partially unscrewed, which permits the locking pin to be forced outwardly from the bore of the sleeve and permits the tool to be readily inserted in the sleeve. The cap 12 is then 10 screwed down tight, and the inclined surface thereof forces the locking pin 20 inwardly, so as to position the tapered end thereof in the groove 19. The rounded or tapered end 24 of the pin permits the tool to readily push 15 the same out of the opening 23, when the cap is unthreaded.

From the foregoing description, it can be seen that an improved right angle handpiece is provided, in which a relatively large bearing surface is provided for the tool carrying sleeve which gives longer wear to the parts and in which an improved and simple means is provided for holding the tool in position in the sleeve.

20 25 When the bearing surfaces of the tool carrying sleeve have become worn, the terminals of the socket 5 may be filed down so as to permit the caps to be threaded further into the socket and thus take up the wear 30 thereof.

In practice, I have found that the form of my invention illustrated in the accompanying drawings and referred to in the above description, as the preferred embodiment, is 35 the most efficient and practical; yet realizing the conditions concurrent with the adoption of my device will necessarily vary, I desire to emphasize that various minor changes in details of construction, proportion and arrangement of parts may be resorted to, when 40 required without sacrificing any of the advantages of my invention as set forth.

What I claim as new is:

1. A right angle handpiece for dental engines including an attaching socket, a transverse socket, a tool carrying sleeve fitted in the transverse socket, a tool detachably fitted in said sleeve, means slidably carried by the sleeve for engaging said tool to hold the 45 same against displacement, and removable caps fitted on the terminals of the transverse socket and arranged to rotatably support the tool carrying sleeve, one of said caps engaging said tool holding means to hold the 50 same in operative position.

2. A right angle handpiece for dental engines comprising an attaching socket, a

transverse socket, a tool carrying sleeve detachably fitted in the transverse socket, a tool detachably fitted in the sleeve, said sleeve having oppositely directed frusto-conical enlargements formed on the terminals thereof, said frusto-conical enlargements forming enlarged bearing surfaces, a transversely sliding pin carried by one 60 of said frusto-conical enlargements and arranged to detachably engage the tool to hold the same against accidental displacement, and removable caps threaded into the terminals of the transverse sockets and having tapered interiors to receive the frusto-conical enlargements to form bearings for the same, the tapered surface of one of said caps engaging the outer end of said pin to force and hold the same in engagement with 65 the tool, as and for the purpose specified.

3. A right angle handpiece for dental engines including an attaching socket, a transverse socket, a tool carrying sleeve fitted in the transverse socket, a tool detachably fitted 70 in said sleeve, a sliding pin carried by said sleeve and arranged to engage said tool to hold the same against accidental movement in relation to the sleeve, and bearing members removably carried by the terminals of 75 the transverse socket, one of said bearing members being arranged to slidably engage said pin to hold the same in engagement with the tool, as and for the purpose specified.

4. A right angle hand piece for dental engines comprising an attaching socket, a transverse socket, a tool carrying sleeve fitted in the transverse socket, and having substantially frusto-conical bearing members formed on the terminals thereof, a tool arranged to be detachably fitted in said sleeve, said tool having an annular groove formed therein adjacent to the upper edge thereof, and a sliding pin carried by the upper frusto-conical 90 member and arranged to engage said groove, and caps threaded into the terminals of said transverse socket and having the interiors thereof tapered to form bearings for the sleeve, said upper cap forming means for 95 holding the pin in engagement with the groove, as and for the purpose specified.

In testimony whereof I affix my signature in presence of two witnesses.

JOSEPH F. NELSON.
